UNITED STATES PATENT OFFICE

HERBERT E. PRESTON, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

FURNACE TUYÈRE

Application filed August 4, 1928. Serial No. 297,494.

My invention relates to means for and method of manufacturing tuyère blocks, and it has for one object the provision of a tuyère that shall be particularly applicable to the 5 furnaces of central-station power plants, wherein highly preheated air is passed through the stoker tuyères. The usual tuyère in such installation deteriorates very rapidly, since it is not only subject to the heating effect 10 of the furnace, but also to that of the preheated air which very frequently exceeds a temperature of 400° F.

Another object of my invention is to provide a tuyère, wherein the portions directly 15 exposed to the heated fuel of the furnace is so associated with another less exposed portion as to permit a limited relative movement therebetween, so that excessive strains are not established in either portion of the tuyère 20 in the event of the uneven heating thereof.

A further object of my invention is to provide a method of making a fuel-engaging element comprising interlocked portions having a limited relative movement, which consists in casting one of said portions about the 25 other, the coefficient of expansion of the material in the cast portion being different from that of the material in the other portion.

A still further object of my invention is to 30 provide a tuyère block of the character described comprising a portion of ferrous material and another portion of carborundum or ceramic material, the ferrous portion being cast about the carborundum portion in interlocking relation therewith.

A still further object of my invention is to 35 provide a tuyère block, wherein a carborundum or ceramic protective block is mounted on a plurality of fins extending from a base member of the tuyère, the fins defining air passages terminating inwardly of the outer edge of the protective block.

A still further object of my invention is to 40 provide a tuyère block which is characterized by its simplicity of design, ease of construction and the absence of bolts or screws for securing together the parts of the tuyère.

Other objects and applications of my invention, as well as details of construction and 45 operation, whereby the same may be prac-

ticed, will be apparent more fully hereinafter, when taken in connection with the accompanying drawings, wherein

Fig. 1 is a longitudinal sectional view of one portion of a furnace embodying my invention;

Figs. 2 and 3 are top plan and side elevational views, respectively, of one of the tuyère blocks shown in Fig. 1;

Fig. 4 is a longitudinal sectional view taken 60 on the line 4—4 of Fig. 2;

Figs. 5 and 6 are top plan and side elevational views, respectively, of the base member of the tuyère block with the carborundum protective blocks removed;

Figs. 7 and 8 are sectional views taken on the lines 7—7 and 8—8, respectively, of Fig. 4;

Fig. 9 is a bottom plan view of the structure of Fig. 5;

Figs. 10 and 11 are detail, top plan and side elevational views, respectively, of one of the carborundum protective blocks shown in Fig. 2;

Fig. 12 is a top plan view of an alternative embodiment of my invention;

Fig. 13 is a longitudinal sectional view taken on the line 13—13 of Fig. 12;

Figs. 14 and 15 are top plan and side elevational views, respectively, of the tuyère 80 shown in Fig. 12; and

Fig. 16 is a transverse sectional view taken on the line 16—16 of Fig. 12.

The usual stoker tuyère is neither designed nor adapted for furnace systems, wherein 85 highly preheated air is employed, inasmuch as the tuyère is subject to contact not only with the hot fuel but also the preheated air, with resulting rapid deterioration.

In accordance with my invention, a tuyère is provided wherein the portion directly exposed to contact with the hot fuel is formed of a non-metallic, wear-resisting material capable of retaining its mechanical and structural strength under the deteriorating effect 95 of the preheated air and hot fuel. The material constituting the exposed surface portion may consist of an inert ceramic material, such as porcelain, or of an artificial compound of carbon and silicon having the trade-name car-

borundum. The remaining surface portion of the tuyère, which is less directly exposed to the heat of the furnace, may be formed of a ferrous material.

5 For purposes of illustration, a furnace employing highly preheated air is shown in Fig. 1. As therein disclosed, an inclined, multiple-retort stoker 1 of the underfeed type extends rearwardly from a furnace opening 2 in a front wall 3 to an ash pocket 4. The stoker 1 may comprise a plurality of series of inclined tuyères 5 and a corresponding plurality of series of retorts 6 alternating therewith, only one series of each, however, being shown. A sufficient number of series of inclined tuyères 5 and retorts 6 is provided to extend across the width of the furnace between side walls 7. A fuel bed, which is illustrated in dot-and-dash lines, may be built 15 upon the grate surface provided by the inclined stoker 1 and slowly moved toward the ash pocket 4 by means of a series of pushers 8 which are actuated by mechanism 9. The retorts 6, in which the pushers are positioned, 20 may receive fuel from a hopper 11 positioned outside of the furnace front wall 3.

The tuyères 5 receive highly preheated air from a wind box 12 positioned under the same and extending across the width of the stoker. 30 The temperature of the air, which is supplied to the tuyères 5 and then discharged into the furnace, may exceed a value of 400° F. The actual passage of the preheated air through the tuyère is illustrated by the dotted-line 35 arrows shown in Figs. 2 and 3. As is customary, the tuyères 5 are made up of a series of tuyère blocks. Each of these blocks comprises a main body portion 13 formed of a flat, thin base plate composed of a ferrous material. 40 The plate 13, of which Fig. 5 is a detail view, comprises a front or outer portion 14 and a rear or inner nose portion 15. An aperture 16 is formed in the front portion for the reception of a projection 17 which depends 45 from an underside 18 of the next higher tuyère block. The opening 16 and the projections 17 are positioned in the longitudinal center line of the tuyère.

The front portion 14 is also provided with 50 a pair of longitudinally-extending side edge portions 19 and 21, which are positioned inwardly of outer edge portions 22 and 23 and interconnected therewith by transverse edge portions 24 and 25, respectively. The edge 55 portions 22 and 23 may be notched at 26 and 27. The transverse edge portions 24 and 25 are projected rearwardly and downwardly by means of the flanges 28 having an inclined front side 29 adapted to be mounted on an 60 adjacent side plate (not shown) and a similarly inclined rear side 31. A lower edge 32 of the rearwardly inclined flange 28 is adapted to rest on an upper side portion 33, Fig. 4, of the next lower tuyère block. The rear 65 or nose portion 15 of the base plate 13 is

provided with curved side edges 34 and 35 which terminate in a transverse edge portion 36 having a forwardly-extending recess 37.

According to my invention, the side and end edge portions of the base plate 13 are 70 protected by a pair of carborundum blocks 38 and 39. The block 38, of which Figs. 10 and 11 are detail, plan and side elevational views, respectively, is provided with an inner edge 41 having an upper beveled portion 42 and a lower vertical portion 43. The beveled edge portion 42 fits against the side edge portions 19 and 34 of the base plate 13 which are provided with a complementary bevel. 75 The bevel of these edge portions is such that the base plate 13 tends to prevent the protective block 38 from moving upwardly. The block 38 is also provided with a transverse edge portion 44, which abuts against 80 the rear edge 36, terminating substantially in the center-line of the tuyère and partially closing the open side of the recess 37. A longitudinal edge 45, extending rearwardly from the transverse edge 44, is positioned 85 immediately adjacent to a corresponding edge portion 46 of the other protective block 39. The edge 45 terminates in a curved portion 47 of an outer edge 48 of the block 38, as shown in Fig. 10. The outer edge 48 extends forwardly into a longitudinal portion 49 which is parallel to the longitudinal portion 19 of the base plate 13. A front edge 51 is positioned immediately adjacent to the edge 24 of the base plate 13. 90

The front portion of the side block 38 is provided with a depending projection 52, Figs. 9 and 10, an end surface 53 of which is beveled complementarily to the surface 31 of the base plate flange 28, the latter constituting an abutment therefor. An underside 54 of the projection 52 normally engages an adjacent upper side portion 55, Fig. 4, of the next lower tuyère block. It is noted that this portion of the protective side block 38 is mounted on the protective block of the next lower tuyère block, but not on the base plate thereof, while the supporting surface 32 of the base-plate projection 28 is supported on the adjacent base-plate portion of the next lower tuyère block but not on the carborundum portion thereof, thereby preventing the separation of the carborundum and base-plate portions of any one tuyère block by the usual forces incident to the mounting of the tuyères as well as furnace operation. 100

A front portion 56 of the inner vertical edge 43 abuts against an adjacent side 57 of a depending flange 58. The flange 58 is extended outwardly by means of a horizontal flange 59 105 which is positioned in spaced relation to the lower edge 32 of the inclined flange 28. The flange 59 extends into the flange 28 at one end, while the other end is provided with a nose portion 61 having an inwardly and for- 110

wardly-extending edge 62. An outer edge 63 of the horizontal flange 59 is positioned inwardly of an edge 64 of the inclined flange 28, as shown in Fig. 5.

5 An inner corner 65 of the block projection 52 is provided with an inwardly-extending horizontal recess 66 adapted to receive the horizontal locking flange 59 of the base plate 13. The flange 59 serves to prevent a vertical movement of the adjacent portion of the protective block, supplementing the locking action of the beveled side edge portions 19 and 42. It is noted, however, that this end of the protective block 38 may be readily disengaged from the horizontal shoulder 59 upon a rearward longitudinal movement thereof. A rear nose portion 67 of the protective block 38 may be supported, so that the upper side thereof is in alignment with 20 the upper side of the base plate 13, by means of a plurality of fins 68, 69 and 71 of progressively decreasing pitch from the side projection 54 of the protective block 38 to the longitudinal center-line of the tuyère block. 25 The end fin 68 forms with an inclined side 72 of the projection 54 an air passage 73. The fins 68 and 69 together form an air passage 74. The fins 69 and 71 form a passage 75. The fin 71 and a corresponding fin 30 72, which is associated with the other protective block 39, are in spaced relation to form an air passage 76 which is in longitudinal center-line of the tuyère block.

Inner or rear ends 77, 78, 79 and 80 of the 35 fins 68, 69, 71 and 72, respectively, are terminated just inwardly of the adjacent edge of the tuyère block nose, so that the several air passages 73, 74, 75 and 76 are not extended to the very edge of the tuyère nose and a 40 marginal air passage 81 is formed interconnecting the air passages 73, 74, 75 and 76. Since the outlet openings of these air passages are positioned inwardly of the exposed nose edge-portion, difficulties heretofore encountered by reason of the molten slag blocking the air-passage outlet openings are substantially eliminated. For example, should molten slag flow over the edge portion of the tuyère block directly in front of the air passage 74, the flow of air through said passage is not interrupted, inasmuch as the air escapes through the transverse marginal air passage 81. The dimensions of the marginal air passage are further increased by beveling the inner ends 77, 78, 79 and 80 of the fins, as shown in Figs. 2 and 3. Thus, the danger of blocking the cross marginal air passage by molten slag is still further decreased.

45 An upward movement of the nose portion of the protective block 38 relative to the supporting fins is prevented by integral tapered lugs 82 and 83 which extend upwardly from the fins 68 and 69 through tapered apertures 84 and 85, respectively, in the protective

block 38. Relative longitudinal movement of the nose portions of the protective blocks 38 and 39, as well as an upward movement thereof away from the supporting fins 71 and 72, is prevented by a lug 86 which extends upwardly through adjacent recesses 87 and 88 in the edge portions 45 and 46 of the blocks 38 and 39, respectively. Longitudinal sides 89, 89 of the integral locking lug 86 are beveled downwardly and inwardly toward the center-line of the tuyère block. Transverse sides 91, 91 are also oppositely beveled so as to lock securely the adjacent nose portions of the protective blocks 38 and 39 in position. The protective block 38 is thus locked in position at its rear end by the integral locking lugs 82, 83 and 86 of the fins 68, 69 and 71-72, and at its front end by the horizontal shoulder 59 of the base plate 13. The beveling of the edges 34 and 41 of the base plate 13 and the protective block 38, respectively, is also such as to prevent an upward movement of the protective block 38. The protective block 39 is similarly mounted, locked in position, and provided with air passages terminating inwardly of the edge thereof so as to form a marginal air passage in communication with the marginal passage 81.

50 The fins 71 and 72 together serve as a supporting lug for the tuyère block, whereby the nose thereof may be mounted on the next lower tuyère block, Fig. 4. Supporting surfaces 92 of the fins 71 and 72 are positioned in the same plane as the supporting surfaces 32 afforded by the base-plate side flanges 28, 28. Additional supporting surfaces 93 for the nose of the tuyère block are provided by the remaining fins associated with the protective blocks 38 and 39.

55 A locking lug for the nose of the tuyère block is formed by a pair of L-shaped projections 94 and 95, Figs. 3 and 4, from the underside of the fins 71 and 72 which are adapted to fit the opening 37 in the nose portion 15 of the next lower base plate 13. The opening 37 is rearwardly undercut, as shown in Figs. 4 and 9, forming beveled locking shoulders 96 and 97 for rearwardly projecting lips 98 and 99 of the spaced projections 94 and 95. The locking projections 94 and 95 are spaced to form an air passage 101 therebetween, so that the main air passages 76 of the next lower tuyère block may not be closed by the locking lug. The opposite sides of the locking projections 94 and 95 abut against adjacent sides 102 and 103 of the fins 71 and 72. The tuyère block is thus locked in desired relation to adjacent tuyère block of the series by means of the locking projection 17 of the next higher tuyère block, which fits the aperture 16 in the front portion 14 of the base plate 13, and by means of the locking lug formed by the projections 94 and 95 which extends into the recess 37 of the next

lower tuyère block and engages the shoulders 96 and 97 thereof.

A preferred method of making the tuyère block shown in Figs. 2 to 11, inclusive, consists in positioning the protective blocks 38 and 39 in a mold (not shown), and then casting the iron base plate 13 with its fins and locking lugs and shoulders. Since the coefficient of expansion of the cast iron is different from that of the carborundum blocks, 38 and 39, when the former cools, shrinkage occurs, so that the carborundum blocks have a limited movement relative to the supporting base plate 13. Such limited movement is of considerable importance during normal operating conditions when the uneven heating of the directly exposed and less exposed tuyère block portions, as well as the differences in the coefficients of expansion of the carborundum and iron portions, results in a relative movement therebetween. If these portions were so rigidly secured together as to prevent such relative movements, then excessive strains would be developed, resulting in the early destruction of the tuyère blocks.

My invention embodies an alternative form of tuyère block, of which Figs. 12 to 16, inclusive, are detail views. As therein shown, the tuyère block comprises broadly a base-plate structure 104 of cast iron, a pair of carborundum side blocks 105 and 106 and a carborundum nose block 107. The side block 105 is interlocked with the base plate 104 by means of flanges 108 and 109, while the opposite side block 106 is secured in position by similar flanges 111 and 112. A rear portion 113 of the base plate 104 is provided with an offset portion forming a vertical wall 114, which is provided with an aperture 115 for the passage of air therethrough. The offset portion is provided with locking shoulders 116 and 117 for securing the carborundum nose 107 in position. An underside 118 of the offset portion rests directly on the next lower tuyère block and is provided with a depending hook 119. The front portion of the base plate 104 is spaced from the next lower tuyère block by the flanges 108 and 111 forming an air passage in communication with the aperture 115, the latter opening into an air passage 121 formed in the carborundum nose block 107. The manufacture of this tuyère block is along the same general lines as that just set-forth for the preceding tuyère block construction, inasmuch as the carborundum protective blocks 105, 106 and 107 are positioned in a mold (not shown), and the iron is then cast around the same to form the base plate 104 with several lockings lugs and shoulders.

While I have shown several embodiments of my invention, for the purpose of describing the same, it appears that various changes and modifications may be made therein with-

out departing from the spirit of my invention.

I claim:

1. A tuyère block comprising a base member, and protective means for said base member having a pair of rearwardly-extending side members terminating in end portions constituting a nose of the tuyère block. 70

2. A tuyère block comprising a base member, protective means for said base member comprising a pair of rearwardly-extending side members terminating in end portions forming a nose of the tuyère block, and means whereby said side members and said base member may be loosely interconnected. 75

3. A tuyère block for a furnace comprising a base member having a rear end and a pair of protective side members, said side members extending rearwardly, so that the rear end of said base member is surrounded and the nose of said tuyère block completed, and means whereby the rear end portion of said side members may be loosely interlocked with said base member. 80

4. A tuyère block for a furnace comprising a base member having a nose portion and a pair of protective members having a nose portion and a front end portion, said protective members extending rearwardly so that the nose portion of said base member is surrounded, and means whereby the nose portion of said protective members may be loosely interlocked with said base member. 85

5. A tuyère block comprising a base member having a rear end portion, and a side member having a rear end portion constituting at least a part of the nose of said tuyère block, the end portion of said side member having an aperture, said base member having an integral locking lug positioned in said aperture, the front end of said side member being beveled and provided with a recess, the adjacent portion of said base member having a complementary beveled portion and also provided with a horizontal locking lug positioned in said recess. 95

6. A stoker tuyère block comprising a base member having an outer edge portion, and a protective member having an inner edge portion, the edge portion of said base member being beveled, the inner edge of said side member having a complementary bevel, whereby said base member may tend to prevent a relative movement between said edge portions in one direction. 105

7. A tuyère block adapted to comprise one of a series provided with an air passage, said tuyère block also having a locking lug adapted to co-act with an adjacent portion of the next adjacent tuyère block, said lug having an air passage constituting one portion of the air passage of said next adjacent tuyère block. 115

8. A tuyère block adapted to comprise one of a series, said tuyère block having a sup-

porting lug, whereby said tuyère may be mounted on the next adjacent tuyère, said supporting lug being provided with an air passage, and a locking lug adapted to extend from said tuyère block into engagement with said next adjacent tuyère block and provided with an air passage, whereby the air passage formed by the supporting lugs of said next adjacent tuyère block may be prevented from being closed by said locking lug.

9. A tuyère block adapted to comprise one of a series provided with a pair of spaced fins extending forwardly from the nose of said tuyère block so as to define an air passage therebetween, said fins serving to support the nose of said tuyère block on the next adjacent tuyère block and also provided with spaced projections forming an air passage therebetween as well as a locking lug.

10. A tuyère block adapted to comprise one of a series, said tuyère block having a raised portion projecting from one face and extending rearwardly from the inner end of said tuyère block, said raised portion being provided with a longitudinal air passage and also a locking lug comprising spaced portions adapted to constitute one part of the corresponding air passage of the next lower tuyère block, said raised portion having a shoulder adapted to engage the locking lug of the next higher tuyère block.

11. A tuyère block provided with a plurality of fins, and a pair of protective blocks forming the nose of said tuyère block, said blocks having abutting edges disposed in substantially the longitudinal center line of the tuyère and having adjacent recesses, an adjacent pair of fins having a single locking lug positioned in said recesses.

12. A tuyère block for a furnace comprising a base member having a nose portion, a plurality of protective members surrounding said nose portion, and means for loosely securing said protective members to the base member.

HERBERT E. PRESTON.
